Hartman Co., St. Louis, Mo., a corporation of Missouri

Application May 31, 1933, Serial No. 48,246

Term of patent 7 years

To all whom it may concern:

Be it known that I, CARL W. BURST, a citizen of the United States, residing in the city of St. Louis, and State of Missouri, have invented a new, original, and ornamental Design for a Combined Doll Wardrobe and Bed or Similar Article, of which the following is a specification, reference being had to the accompanying drawing, forming part thereof.

The figure is a perspective view of a combined doll wardrobe and bed or similar article, showing my new design.

The bed is securely attached to the wardrobe.

I claim:

The ornamental design for a combined doll wardrobe and bed or similar article, as shown and described.

CARL W. BURST.
